UNITED STATES PATENT OFFICE.

MAURICE N. WEINSTEIN, OF EAST CLEVELAND, OHIO.

CLEANER AND GAUGE FOR WINDING MACHINES.

Application filed March 8, 1922. Serial No. 541,947.

To all whom it may concern:

Be it known that I, MAURICE N. WEINSTEIN, a citizen of the United States, residing at East Cleveland, in the county of Cuyahoga and State of Ohio, have invented a certain new and useful Improvement in Cleaners and Gauges for Winding Machines, of which the following is a full, clear, and exact description, reference being had to the accompanying drawings.

This invention is a novel construction of cleaner and gauge for use in connection with machines for winding wool, silk or other material, the object of the invention being to provide a cheap and simple device which can be used in connection with any of the standard types of winding machines and one which will be more durable than the devices now in use and also capable of exceedingly fine adjustments.

Another object of the invention is to so construct and arrange the parts as to facilitate the introduction of a thread or yarn to the device, and a still further object is to so construct the adjusting parts of the device that when once adjusted they will remain fixed in such adjusted positions.

It is well known that wool, silk, cotton and similar thread material as manufactured contains certain imperfections either in the way of foreign matter adhering to the thread, or excessive material at certain points, and inasmuch as the uniform dimension of thread or strand is desirable in knitting and weaving, it is customary in winding the thread or strand to clean or scrape the same so as to remove all surplus or foreign matter so that the thread or strand as finally wound will be of uniform dimension.

While cleaners or scrapers have been employed in connection with various types of winding machines, they have proven only partially successful owing to the difficulty of maintaining accurate adjustments, and for various other reasons. As before stated, the object of my invention is to provide a simple and easily adjusted device which will remedy all of these various defects.

With these objects in view my invention consists in the novel features of construction and also in the manner of combining or arranging the same, all of which will be hereinafter fully described and set forth in the appended claims.

In the drawings forming part of this specification, Fig. 1 is a face view of one

form of cleaner or scraper embodying my invention together with a guide arranged in advance thereof, both the cleaner and guide being connected to a bar attached to the frame of a winding machine; Fig. 2 is a plan view showing the cleaner and guide, bar and arms connecting the cleaner and guide to the bar; Fig. 3 is a side view of the cleaner arranged upon the upper end of a vertical arm; Fig. 4 is a face view of the same; Fig. 5 is a view from the opposite side; Fig. 6 is an enlarged sectional view, partly in elevation, of the fixed and movable blade carrying members and means for adjusting the same; Fig. 7 is a detail sectional view on the line 7—7 of Fig. 6; Fig. 8 is a detail sectional view on the line 8—8 of Fig. 6, the screw being shown in elevation; and Fig. 9 is a detail view showing a portion of the movable blade carrying member.

In the practical embodiment of my invention, I employ a supporting arm A which is connected to any suitable portion of the machine frame or to a bar A' attached to said frame, as shown in Figs. 1 and 2 in which case the arm A is arranged horizontally, whereas in Figs. 3, 4 and 5, the arm A is shown connected directly to the machine frame and in vertical position. The cleaner or scraper proper comprises two block-like members B and C to which are connected the cleaner or scraper blades D and E, respectively. The member B, which I term the fixed member, is rigidly connected to the arm or rod A, the lower end of the fixed member being bored both vertically or horizontally to receive the end of the arm, and a set screw F is employed to securely connect the said member B to the arm or rod A.

The movable member C is adjustably connected to the fixed member B by means of a differential screw G and a threaded bushing H, the bushing H being both internally and externally threaded, the interior threads being somewhat coarser than the exterior threads. The bushing H is screwed into the fixed member B and is rigidly secured by means of a lock nut H'. The screw G consists of the reduced portion G' having a thread corresponding to the interior thread of the bushing H while the larger portion G² has a thread corresponding with the exterior thread of the bushing H and screws into the threaded bore I of the mov-

able member, and the head portion G^2 of the screw is adapted to fit into the circular recess I' communicating with the threaded bore I . The head of the screw is provided 5 with a polygonal recess or socket G^4 into which the correspondingly shaped end of a wrench can be placed for the purpose of turning the screw in either direction and the periphery of the screw head is provided 10 with graduations G^5 which cooperate with an indicating mark placed upon the blade E and by means of which the amount of adjustment can be readily gauged. It is obvious that by turning the screw in one direction the movable member C will be brought 15 toward the fixed member and when turned in the opposite direction will be positively moved in the opposite direction and by having the differential screw and the bushing 20 for effecting this lateral movement, it is obvious that I am able to effect a very fine adjustment, and by having the bushing adjustable as well as the screw, any inaccuracies which might occur due to the wear of 25 parts can be corrected. In order to guide the block C in its movements and insure parallelism at all times, I employ a guide piece K which is rigidly connected to the block C by a screw K^2 and projects laterally 30 therefrom. This guide piece K is preferably square in cross section and fits into a correspondingly shaped recess cut in the face of the block C and the other end of the guide piece works in a correspondingly shaped 35 guideway K^2 cut in the face of the fixed member B as most clearly shown in Figs. 3, 5, 6 and 7. The blades D and E are preferably made of good quality of steel and are not only machined along their edges 40 D' and E' , but also have their outer faces machined so that their front edges are in reality shearing edges so that small threads projecting from the main thread or strand will be sheared or trimmed off as it passes 45 between the blades. The blades D and E are attached to the front faces of the fixed and movable members by means of screws D^3 and E^3 , respectively, said screws passing through the blades and entering threaded 50 holes produced in the fixed and movable members and in addition to the screws D^3 and E^3 I provide a set screw D^4 which works through a slot D^5 produced near the end of the blade D , the shank of the screw D^4 working into a threaded hole D^6 produced 55 in the guide piece K , it being understood that when it is desired to adjust the blades through the medium of the differential screw the set screw D^4 is loosened and then 60 tightened again after the desired adjustment has been had, the guide piece K working in the transverse recess in the fixed member during the adjustment. The front faces of the fixed members B and C are 65 planed off so as to leave guiding flanges B'

and C' at the outer sides of said members and the outer side edges of the blades are fitted firmly against these stop flanges and by having the outer edges accurately machined and the contacting faces of the 70 flanges correspondingly machined, I obtain great accuracy in the positioning of the blades upon the fixed and movable members. The flanges B' and C' are interrupted or removed for the placement of the guide 75 piece, and the flange C' and a portion of the fixed member C is also removed in order to expose the graduated head of the adjusting screw. Near the lower end of the fixed member C , I produce a recess L and in the 80 fixed member B I produce a transverse bore M which is adapted to align with the recess L and in this recess and bore I arrange the glass or porcelain roller N over which the thread passes, and this roller is held against 85 lateral displacement by means of a screw plug O which is screwed into the outer end of the transverse bore M , but the roller has a limited amount of lateral movement and at the same time turns freely in the bore 90 and recess so that the roller will turn freely and move from side to side so that wear upon the surface thereof will be reduced to a minimum. Should it be necessary to remove the roller at any time and a new 95 one substituted, it can be quickly accomplished by unscrewing the plug O , taking out the impaired roller, inserting a new one and replacing the plug.

It will be noted that the transverse bore 100 is threaded only a portion of the way so that it will be impossible to screw the plug into contact with the roller. The fixed member B is preferably made somewhat longer than the movable member C and the blade 105 D is also made somewhat longer and is rounded at its extreme lower end. The blade E is formed with the downwardly and outwardly inclined portion E^4 below the end of the movable member and then is 110 provided with the upwardly and outwardly extending portion E^5 , the end of which is rounded and the lower outer edge of the movable member C is also cut away and rounded as most clearly shown at C^2 in Figs. 115 2, 5 and 9. Shaping the blades in the manner herein described facilitates the introduction of the thread or strand into the space between the cleaning blades irrespective of whether the blades are projecting downwardly, upwardly or laterally.

It will thus be seen that I provide an exceedingly cheap and simple device which can be quickly and easily connected to any of the present standard types of winding 125 machines and can be arranged in various positions according to the direction of travel or position of the thread which is being cleaned and gauged. By means of the differential screw and bushing, I am able to 130

obtain positive movement in either direction of the movable member, and furthermore I am able to obtain exceedingly fine adjustments during such movements, and 5 in case any inaccuracies should become apparent due to the wear of parts, this can be readily compensated by the adjustment of the bushing in the fixed member.

The manner of arranging the glass or 10 porcelain roller between the fixed and movable member renders the movement of said glass or porcelain roller free and easy both rotatively and laterally, and the roller can also be quickly removed and replaced when 15 desired. By having the guide flanges upon the outer sides of the fixed and movable members and placing the blades directly against said flanges, said blades are quickly and easily positioned in proper perpendicular positions, and by having both the 20 front faces and the contiguous edges of the blades machined true, sharp edges or corners are provided, which trim off any small threads or other projections which might ordinarily pass between the gauged blades 25 without being sheared. The peculiar shape of the lower or outer end of the blade attached to the movable member has been found to be extremely helpful in quickly 30 and easily guiding the thread or yarn into the converging space between the blades. The guide piece K which is attached to one of the members and movable in the other member insures the proper parallelism of 35 the movable member with reference to the fixed member and consequently maintains the blades in proper parallel relation at all times.

Having thus described my invention, 40 what I claim is:

1. In a device of the kind described, a fixed blade carrying member, a movable blade carrying member, each having a blade connected thereto, a guide connected to one 45 member and working in the other member, a bushing arranged in one member, and a differential screw working in one member and the said bushing for adjustably connecting the two members.

2. In a device of the kind described, a fixed member, and a movable member, each having a guide flange along its outer edge, blades attached to the faces of said members and abutting against the said flanges, the 55 blade attached to the fixed member projecting beyond said member, and the blade attached to the movable member extending laterally at an angle from the end of said member.

3. In a device of the kind described, a fixed member and a movable member adjustably connected, one of said members having a recess, the other member having an opening in alignment with said recess, a 65 roller positioned in said recess and opening,

and a plug closing one end of said opening and retaining said roller against lateral displacement.

4. In a device of the kind described, a fixed member and a movable member, a bushing adjustable in the fixed member and means for locking the same, and a differential screw having its reduced end working in the bushing and its enlarged end working in movable member, said screw having 70 a graduated head, the movable member having an indicating point for cooperation with the graduated head of screw.

5. In a device of the kind described, a bar adapted to be attached to a frame, an arm 80 adjustably connected to said bar, and carrying an eye at its free end, a second arm also attached to said bar, a member fixed to said second arm, a second member adjustably connected to the first member, and means for 85 moving the same, and blades connected to said members and having their contiguous edges spaced apart, said space being in alignment with the eye carried by the first named arm. 90

6. In a device of the kind described, a fixed member and a movable member, each having a flange at its outer edge, a blade attached to the face of each member and contacting with the flange, the faces and the 95 contiguous edges of said blades being machined, so that parallel spaced cutting edges will be provided and between which the thread is adapted to pass.

7. In a device of the kind described, a 100 fixed member and a movable member, a guide piece attached to the movable member and slidable in the fixed member, a blade fixed to each member, the blade on the fixed member being slotted, a set screw passing 105 through said slot and entering the guide piece.

8. In a device of the kind described, a fixed member and a movable member adjustably connected thereto by a differential 110 screw, and a threaded bushing, a blade fixed to each member, the blade of the fixed member extending downwardly, and the blade of the movable member extending obliquely 115 downwardly and then upwardly, the lower rear corner of the movable member being rounded off.

9. In a device of the kind described, a fixed member, and its blade, a movable member, and its blade, a guide piece connected to 120 the movable and working in the fixed member, a threaded bushing adjustably mounted in the fixed member, a differential screw working in the movable member and in the bushing of the fixed member, said movable member having a recess and the fixed member an opening in alignment therewith, a roller in said recess and opening and a plug for closing said opening at one end. 125

10. In a device of the kind described, a

fixed member having a threaded bushing, of a movable member, and a screw having one portion of reduced diameter with a coarse thread adapted to engage said bushing, and 5 a portion of finer thread engaging the movable member, and a guide piece carried by one of the members and working in the other member.

11. In a device of the kind described, an 10 arm, a member bored vertically and hori-

zontally to receive the end of said arm, said member having a threaded bushing, and a second member having a differential screw passing therethrough, one end of said screw working in the threaded bushing and the 15 other end in the movable member, and blades attached to said members.

In testimony whereof, I hereunto affix my signature.

MAURICE N. WEINSTEIN.
